US0D1100578S

(12) **United States Design Patent** (10) **Patent No.:** **US D1,100,578 S**
(45) **Date of Patent:** **** Nov. 4, 2025**

(54) **HAND MIXER**

(71) Applicant: **WHIRLPOOL CORPORATION**,
Benton Harbor, MI (US)

(72) Inventors: **John W. McConnell**, St. Joseph, MI
(US); **Brandon Tyler Mock**, St. Joseph,
MI (US); **John Jay Myers**, Saugatuck,
MI (US); **Nicholas Hill Schutte**, St.
Joseph, MI (US); **Rex D. Wilson**,
Stevensville, MI (US)

(73) Assignee: **WHIRLPOOL CORPORATION**,
Benton Harbor, MI (US)

(**) Term: **15 Years**

(21) Appl. No.: **29/984,270**

(22) Filed: **Jan. 14, 2025**

Related U.S. Application Data

(63) Continuation of application No. 29/853,752, filed on
Sep. 19, 2022, now Pat. No. Des. 1,064,719.

CLAIM

The ornamental design for a hand mixer as shown and
described.

DESCRIPTION

FIG. 1 is a top perspective view of a hand mixer according
to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom perspective view thereof.

(Continued)

The portions of the article shown in broken line form no part of the claimed design.

1 Claim, 6 Drawing Sheets
